UNITED STATES PATENT OFFICE.

JOHN T. RIDDELL, OF EVANSTON, ILLINOIS.

ATHLETIC SHOE.

Application filed November 13, 1923. Serial No. 600,495.

This invention relates to athletic shoes and has for its object the provision of an improved shoe of this character, especially adapted for wear by foot-ball players, having substantially inflexible means disposed inside of the shoe which serves as a common anchorage for a plurality of spaced exterior tread members or cleats disposed upon the bottom of the shoe.

10 Another object of the invention is to provide such anchoring means with a plurality of exteriorly projecting extensions upon each of which may be detachably mounted a suitable tread member.

15 Other objects will appear hereinafter.

The invention consists in the combinations and arrangements of parts hereinafter described and claimed.

The invention will be best understood by 20 reference to the accompanying drawings forming a part of this specification, and in which,

Fig. 1, is a bottom plan view of a shoe, showing the invention applied thereto, a 25 portion of the shoe being broken away to expose the interior construction thereof, and

Fig. 2, is a sectional view of the invention on the line 2—2 of Fig. 1.

Referring to the drawings, a shoe of any 30 usual or desired construction is illustrated, such shoe having the usual vamp 3, insole 4, welt 5, and outer sole 6. Preferably disposed between the insole 4 and the sole 6 is a relatively thin substantially inflexible plate 35 7, preferably of steel, such plate being provided with a plurality of studs or extensions 8, welded thereon, or otherwise secured thereto, such extensions projecting outwardly through and beyond the sole 6, the 40 outer ends of the extensions preferably being threaded. A plurality of tread members or cleats 9 may be secured by any suitable means to the extensions 8; preferably each of the tread members 9 is provided with a 45 threaded member 10 embedded therein,

which is adapted to be threaded upon an extension 8, as shown, thus detachably securing said tread members in operative position. Similar anchoring means together with similar tread members may be applied to the 50 heel of the shoe in the manner described.

By this arrangement a common inflexible anchorage is provided for a plurality of tread members which are detachably fastened thereto, the construction being such 55 that the tread members cannot become displaced or forced out of alignment with respect to each other, and are retained in the most advantageous position beneath the foot of the wearer.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having described my invention what I claim as new and desire to secure by Letters Patent is:

The combination with a shoe, of a metallic plate arranged against the inner side of the sole thereof; a plurality of spaced threaded studs rigidly and permanently secured to said plate and extending downwardly through the sole of the shoe; and a plurality of tread members of relatively 75 softer material, each of said tread members having a threaded engagement with one of said studs, and each of said tread members resting against the bottom of the sole and adjustably clamping the sole against said 80 plate, substantially as described.

In testimony whereof I have signed my name to this specification.

JOHN T. RIDDELL.
